PAUL SCHOU, OF COPENHAGEN, DENMARK.

PUMP.

1,250,232.

Specification of Letters Patent. Patented Dec. 18, 1917.

Application filed May 8, 1917. Serial No. 167,310.

To all whom it may concern:

Be it known that I, PAUL SCHOU, of Copenhagen, in the Kingdom of Denmark, have invented certain new and useful Im-
5 provements in Pumps, of which the follow-
ing is a full, clear, and exact description.

This invention refers to a pump, principally characterized in that the reciprocating movement of the piston in its stationary cylinder is caused by a rotating eccentric with two roller-tracks—one outer and one inner—each having its corresponding roller disposed on the piston, so that the one roller-track with its roller pushes the piston into, 10 and the other roller-track with its roller pulls the piston out of the cylinder.

This driving-mechanism, especially in single-action cylinders, makes it possible for the driving shaft to be journaled close to 20 the end of the cylinder, and thus the construction is made "short," which advantage may be still more enhanced by making recesses in the cylinder for the roller-tracks and by journaling the rollers in correspond- 25 ing recesses in the piston, so that the end surface of the piston, in one of the dead-center positions, is in the immediate vicinity of the driving-shaft.

Another advantage in this construction is 30 the very slight friction between the power-transmitting members, especially when the rollers run on balls.

Another advantage consists in that one is not restricted to the piston movement which 35 is characteristic of crank and connecting-rod or eccentric and eccentric-strap, with maximum speed in the middle of the stroke and even transition between the one stroke and the next, it being possible to vary the 40 shape of the roller-tracks in different ways, from the circular shape, thereby, for instance, attaining a maximum speed at other periods of time than the middle of the stroke, or attaining the advantage that the 45 piston, in one or both dead-center positions, is at rest during longer periods, which is of importance in pumps which run at high speed.

This invention is especially suitable for 50 pumps with two or more cylinders, inasmuch as two cylinders may be disposed opposite each other with their common eccentric (roller-track) between their ends, which face each other; or several cylinders 55 may be disposed in the form of a star around a common eccentric. Owing to the "short"

construction which characterizes this invention, such a multi-cylindered pump will, in its entirety, only take a comparatively small space.

When a pump of this kind is to be used for pumping air or gas, for instance, as compressor or vacuum pump, the cylinder or cylinders are connected with a chamber or a pipe which contains a sealing or lubricating means in such a manner that the latter will constantly be spread out on a zone of the piston or pistons and will be carried from there out through the outlet valve, together with the air or gas, and then be carried 60 automatically back to the aforesaid pipe.

One form of construction of a 2-cylinder air-pump of the kind here set forth, with the aforesaid circulation of a sealing or lubricating means is diagrammatically 65 shown, by way of example, in the drawing in two sections at right angles to each other, in Figs. 1 and 2 respectively.

In each of the cylinders 3, there is at a certain comparatively small distance from 80 the outer end, which is normally closed by the movable cylinder-head, 4, which forms an outlet-valve, a ring-shaped groove 5 connected with the suction-pipe 6, and at a certain distance inside of this ring-shaped 85 groove there is another ring-shaped groove 7 connected with a pipe 8.

In the inner end of the cylinders there are recesses 10, and in the inner end of the pistons 11 there are corresponding recesses 12. 90 In these recesses the eccentric fastened on the shaft 13, which eccentric has an external roller-track 14 and an internal inner roller-track 15, can freely rotate. In the recesses 12 on the pistons, there are disposed rollers 95 16 and 17, which press against the roller-tracks 14 and 15 respectively.

When the shaft 13 is turned, preferably with great speed, the shaft being, for instance directly coupled to an electro-motor 9, 100 the pistons 11 will be alternately moved in and out of the cylinders 3. The length of stroke is essentially only equal to the width of the ring-shaped groove 5, plus the distance of the latter from the outer end of 105 the cylinders, plus the distance that the outlet valve 4 is shifted by the piston.

In the pipe 8 there is a sealing or lubricating means which, from the ring-shaped groove 7, can spread itself out in the form of 110 a film; or thin coating, on the piston. During the suction period, which is the period

2
during which the piston, by the action of the roller 17 and the roller-track 15, is pulled in toward the shaft 13, thereby being removed from the outlet-valve, or the cylinder-head 4 which, by some means of pressure 18, for instance a spiral spring, is pressed up against the end of the cylinder, the sealing or lubricating means spread out like a film will, partly due to the movement 16 of the piston itself and partly due to the suction, be carried all the way to the end-surface of the piston and to that part of the cylinder which surrounds the working-chamber. When the ring-shaped groove 5 is opened by the piston, the working-chamber is filled with the gaseous medium from the suction-pipe 6, and, together with this gaseous medium, the lubricating or sealing means will be driven out through the outlet-valve 4 during the ensuing pressure period.

In the shown example the pressure-valve 4 is covered by a head in the form of a cap 19 which, on its top, has an opening 20 for the gaseous medium and, at the bottom, an opening 21 for the sealing or lubricating means, which can be conducted from here to a reservoir 22. The opening 21 may, of course, be continued in the shape of a pipe. A suitable pump 23, which can be driven by another eccentric 24 on a shaft 13, pumps the sealing or lubricating means from the reservoir 22, or the opening 21, into the pipe 8. The use of a special pump 23 for accomplishing the automatic circulation of the sealing or lubricating means has the advantage that the feed-pressure of the latter (the pressure in the ring-shaped grooves 7) can thereby be rendered independent both of the pressure-condition in the air-pump, and eventually also of the outer air-pressure and of the differences of altitude.

Opposite to the circulation pump 23, there is disposed another pump 25, which, with the use of the pump 3, in a vacuum refrigerating plant, can serve for the circulation of salt water or some other refrigerating means.

In the shown example, the pump 3, is disposed on the casing of the electro-motor, and the reservoir 22 is formed of the upper part of said casing, a cap 26, in the capacity of oil-lock, being disposed around the bearing of the shaft 13. The whole is surrounded by a suitable jacket 27. The relative position 55 of pump and electromotor is, however, obviously immaterial. The invention is not at all dependent upon the coupling to any definite motor, and, on the whole, the shown details may be altered in many ways without 60 deviating from the invention.

I claim:—

1. A device of the character described comprising a cylinder provided near its outer end with an annular inlet for air to be compressed and with an annular sealing

groove between said air inlet and the open end of the cylinder, a movable head adapted to serve as an outlet valve, elastic means for holding said head normally closed against the outer end of said cylinder, means for supplying air to said annular air inlet, means for supplying a liquid to said annular sealing groove, a reciprocatory piston in said cylinder, and means for actuating said piston.

2. A device of the character described comprising a cylinder provided near its outer end with an annular inlet for air to be compressed and with an annular sealing groove between said air inlet and the open end of the cylinder, a cap covering the outer end of said cylinder and provided with a guideway, a movable head disposed between said cap and the bore of the cylinder and provided with a stud engaging said guideway, a spring disposed between said cap and said head and adapted to hold said head normally in closed position against said cylinder, means for supplying air to said annular air inlet, means for supplying a liquid to said annular sealing groove, a reciprocatory piston in said cylinder, and means for actuating said piston.

3. The combination of cylinders having their inner ends adjacently disposed and provided at their outer ends with outlet valves and adjacent thereto with annular air inlets and adjacent to said air inlets with annular sealing grooves, reciprocatory pistons in said cylinders provided with rollers, a driving shaft disposed between said cylinders transversely thereof, a cam on said shaft having internal and external tracks engaged by said rollers, means for supplying air to said annular air inlets, and means for supplying a sealing liquid to said annular sealing grooves.

4. The combination of cylinders having their inner ends adjacently disposed and provided at their outer ends with outlet valves and adjacent thereto with annular air inlets and adjacent to said inlets with annular sealing grooves, reciprocatory pistons in said cylinders provided with rollers, a driving shaft disposed between said cylinders transversely thereof, a cam on said shaft having internal and external tracks engaged by said rollers, means for supplying air to said annular air inlets, a pump for supplying a sealing liquid to said annular sealing grooves, and a cam on said shaft for actuating said pump.

5. The combination of cylinders having their inner ends adjacently disposed and provided at their outer ends with outlet valves and adjacent thereto with annular air inlets and adjacent to said air inlets with annular sealing grooves, reciprocatory pistons in said cylinders provided with rollers, a driving shaft disposed between said cylinders transversely thereof, a cam on said

shaft having internal and external tracks engaged by said rollers, means for supplying air to said annular air inlets, a pump for supplying a sealing liquid to said annular sealing grooves, a cam on said shaft for actuating said pump, and a supplemental pump actuated by said last named cam.

6. The combination of cylinders having their inner ends adjacently disposed and 10 provided at their outer ends with outlet valves and adjacent thereto with annular air inlets and adjacent to said air inlets with annular sealing grooves, reciprocatory pistons in said cylinders having recesses in their 15 inner ends and provided with rollers dis-

posed in said recesses, a driving shaft disposed between said cylinders transversely thereof, a cam on said shaft having internal and external tracks engaged by said rollers, means for supplying air to said annular 20 air inlets, and means for supplying a sealing liquid to said annular sealing grooves.

In testimony, that I claim the foregoing as my invention, I have signed my name in presence of two subscribing witnesses.

PAUL SCHOU.
